HENRY FORNCROOK, F. J. SHEPPERD, AND ANDREW GARTON, OF WATERTOWN, WISCONSIN.

Letters Patent No. 79,336, dated June 30, 1868.

IMPROVEMENT IN HOP-PICKERS.

The Schedule referred to in these Letters Patent and making part of the same.

TO ALL WHOM IT MAY CONCERN:

Be it known that we, HENRY FORNCROOK, F. J. SHEPPERD, and ANDREW GARTON, of Watertown, in the county of Jefferson, and in the State of Wisconsin, have invented an Improvement in Hop-Pickers; and do hereby declare that the following is a full, clear, and exact description thereof, reference being had to the accompanying drawings, making a part of this specification, in which—

Figure 1 is a top view.

Figure 2 is an elevation of the front side.

Figure 3 is an elevation of the back side.

Figure 4 is a sectional side elevation.

Figure 5 is an elevation of the front end.

Figure 6 shows the means used for imparting motion to the shaker.

Letters of like name and kind refer to like parts in each of the figures.

This invention is designed to facilitate the heretofore tedious process of stripping the hops from vines, and consists in the combination and arrangement of the several parts, as herein described.

A represents the framework and casing enclosing the mechanism of the machine.

B is a cylinder or picker, composed of two wheels fastened to a shaft, with their rims connected by flat strips, each of which contains a row of pins or teeth projecting outwards. If driven by hand, the picker is actuated by a crank, C, but if other power is applied, a pulley may be substituted. The picker is covered by a drum, a^1 , which can be removed when necessary.

D represents a shaft, situated in front of the picker B, projecting from which are four rows of pins, of sufficient length to pass between the teeth of the picker.

Motion is imparted by means of a pulley, d, connected by a belt with the counter-shaft E.

The counter-shaft E has a balance-wheel, and is provided with pulleys for giving motion, through belts, to the several parts of the machine.

F represents a screen or bolt, made of wire cloth, in the form of a hollow cylinder, and fastened to a shaft, f, which is made to revolve by means of bevelled gear G, to one of which is attached a pulley, g^1 , connected by a belt with the counter-shaft E.

The bolt F is lower in front than at the back end, and can be adjusted to any desired angle by raising or lowering the strip a^2 , through which the front end of the shaft f passes, the frame or jack, g^2 , supporting the back end, being secured to the frame A by one screw upon each side, allowing it to turn as the front end is raised or lowered.

Directly below the bolt is a tray or shaker, H, the upper end of which rests upon a cross-bar, a^3 , to which it is connected by a bolt, while the lower end is suspended by straps, fastened to the corners, and attached to the frame.

The shaker inclines downward at the same angle as the bolt. It also has a slight incline towards the back of the machine. A reciprocatory motion is imparted to its lower end by means of the rod I, crotch K, and rod L, which is connected to a pulley upon the back-end of the counter-shaft E.

Upon the lower back corner of the shaker is a spout, made of sheet metal, passing into an opening in the lower end of an elevator, M, of the usual form and construction, which is attached to the back side of the machine, and is driven by a belt from a pulley, e, upon the end of the counter-shaft E.

Upon the feed-board N, and directly in front of the picker, is a self-feeding attachment, composed of three rollers, the two lower ones, O O, being round, and turning loosely upon their axles, while the upper, P, is provided with leaves, and driven by a belt from the shaft of the picker.

Above the boxes in which the journals of the roller P turn are placed spiral rubber or other springs, for the purpose of securing a constant pressure upon the vines passing through.

The operation of this machine is as follows, viz: The arms are stripped from the vines, and passed into the machine through the feed-rollers, when they encounter the teeth of the picker, which effectually separate the hops from the vines, and pass both through the trough, upon the opposite side, into the screen, where the hops drop into the shaker, from whence they pass through the elevator into sacks or other articles provided for their reception, while the vines and leaves pass out through the lower part of the bolt.

The feed-rollers allow the vines to be drawn into the machine as fast only as they are completely separated from the hops.

The shaft D keeps the teeth of the picker free from vines, which would otherwise soon clog them and stop the machine.

The work performed by this machine is more thoroughly done, and much cheaper, than if done in any other manner, and enables the grower to place his hops in market earlier and at less cost than he could otherwise do.

Having thus fully set forth the nature and merits of our improvement, what we claim as our invention, and desire to secure by Letters Patent, is—

1. The manner of adjusting the incline of the bolt F, by means of the movable strip α^2 , in combination with the jack g^2 , suspended to the frame by one screw upon each side, substantially as herein shown and described.

2. The combination and arrangement of the picker B, cleaner D, bolt F, shaker H, and feed-rollers O O and P, in the manner and for the purpose substantially as herein set forth.

3. In combination with the above, the elevator M, arranged substantially as herein specified.

In testimony that we claim the foregoing, we have hereunto set our hands and seals, this 6th day of May, 1868.

HENRY FORNCROOK. [L. S.]

F. J. SHEPPERD. [L. S.]

ANDREW GARTON. [L. S.]
